John M. Penn.

ATTORNEY

UNITED STATES PATENT OFFICE.

JOHN M. PENN, OF RED OAK, IOWA.

TONGUE-SUPPORT FOR VEHICLES.

1,265,503.

Specification of Letters Patent.

Patented May 7, 1918.

Application filed October 9, 1915. Serial No. 55,029.

To all whom it may concern:

Be it known that I, JOHN M. PENN, a citizen of the United States, residing at Red Oak, in the county of Montgomery and State 5 of Iowa, have invented certain new and useful Improvements in Tongue-Supports for Vehicles, of which the following is a specification.

My invention relates to tongue supports 10 for vehicles and more particularly to an adjustable spring support for wagon tongues.

The primary object of my invention resides in the provision of a novel supporting means for resiliently maintaining a wagon 15 tongue in position on a vehicle.

Another object of my invention resides in the provision of a novel clamping means for association with a tongue and resilient supporting means for maintaining the tongue 20 in various adjusted positions as well as resilient connecting means between the clamping means and resilient supporting means for maintaining the tongue in a horizontal position when the wagon and team are on a level 25 and permitting the tongue to be either raised or lowered as will be necessary when starting up a steep grade or when dumping a load of dirt or material and returning the tongue to a horizontal position when a level is reached 30 by a wagon and team.

A still further object of my invention resides in the provision of a device of the character described that is simple in construction, efficient in operation and one that 35 can be manufactured and placed on the market at a minimum cost.

In the drawings:

Figure 1 is a top plan view of my invention associated with a vehicle and a tongue 40 therefor;

Fig. 2 is a side elevational view of my invention associated with a vehicle and a tongue therefor;

Fig. 3 is an enlarged perspective view of a 45 portion of the clamping means;

Fig. 4 is an enlarged perspective view of the connecting bar.

Referring more particularly to the drawings in which similar reference numerals 50 designate like or corresponding parts throughout the different views, I provide an axle 1, the respective ends of which have supporting wheels 2 rotatably associated

therewith. Hounds 3 extend forwardly of the axle and have a tongue 4 pivotally connected thereto through the medium of angle brackets 5 and a nut and bolt arrangement 6, the opposite end of the brackets being rigidly connected to the hounds through the medium of suitable fastening devices 7. A 60 whiffletree clip 8 has one end connected to the upper surface of the tongue adjacent the hounds and has its free end offset and adapted to pivotally connect a draft device to the tongue. 65

For the purpose of resiliently supporting the tongue, I have provided my improved resilient means in this instance comprising an elliptical spring 9 formed preferably of a plurality of superposed sections, the outer 70 end of the spring having a hinge section pivotally connected thereto through the medium of a suitable pin 10, the hinged section being rigidly connected through the medium of suitable fastening devices 11 to the under 75 surface of the tongue slightly in advance of the point at which a draft device is attached. The opposite end of the spring 9 is supported in slidably engagement with the under surface of the axle 11 through 80 the medium of a suitable strap 12, carried by the under surface of the axle 1.

In order to adjustably control the tension of the spring 9 with respect to the tongue 4, I have provided my improved clamping 85 means in this instance including similarly formed side bars 13, the upper ends of which are rounded and screw threaded as illustrated by the numeral 14, the opposite ends 90 being offset to provide spring engaging portions 15. These bars 13 are arranged upon opposite sides of the inner end of the tongue slightly in the rear of the whiffletree clip 8, and have engaged about their screw threaded ends suitable adjusting elements preferably 95 nuts 16, which support a strap 17. This strap is bent upwardly intermediate its ends and is arranged to abut the under surface 100 of the tongue and the bars have further associated therewith another strap 18 which is arranged about the screw threaded ends 14, the latter also receiving suitable fastening elements, preferably nuts 19. The nuts are adjusted so that the straps 17 and 18 are 105 arranged in substantially rigid engagement with the tongue. The spring engaging por-

tions 15 are provided with spaced openings adjacent their lower ends through which pass bolts 20, the shanks of the bolts having sleeve rollers 21 rotatably associated therewith which rollers are incidentally arranged respectively upon the upper and lower surfaces of the spring 9. The projecting screw threaded ends of the bolts 20 are engaged by suitable fastening devices, preferably 10 nuts 22.

For the purpose of maintaining the tongue 4 normally in a horizontal position and to permit the tongue to be either raised or lowered as will be necessary when starting 15 up a steep grade or dumping a load and restoring the tongue to a horizontal position when a level is reached, I have provided my improved connecting means which cooperates with both the clamping means and the resilient supporting means. The connecting means in this instance includes an elongated flat bar 23 one end of which is bent upwardly to provide a hook 24 while the opposite end is bent in an opposite direction 20 to provide an open retaining loop 25. This bar is placed on the upper surface of the tongue and secured in intimate contact therewith through the medium of the clamping strap 18, the bent portion of which 25 straddles the bar 23, while the hook 24 abuts the strap 18. The loop 25 is extended slightly beyond the inner end of the tongue 30 and is engaged by one end of a coil spring 26, the opposite end of which is connected to 35 a loop 27 which is in turn connected to the spring 9. The springs 26 and 9 are of a different degree of resiliency and are connected so that the action of one modifies the action of the other. The tension of the 40 spring 26 is such that when it co-operates with the spring 9 and the clamping means, the tongue will be normally held in a horizontal position yet the tongue may be either raised or lowered against the tension of the 45 springs, the spring 26 also serving to absorb shock transmitted to the spring 9.

The operation of my invention is as follows:

The tension of the springs 9 and 26 is such 50 that the tongue is normally maintained in a horizontal position. Should the tongue be either raised or lowered when the vehicle is ascending a steep incline or when the load of material is being dumped as soon as the 55 vehicle reaches a level incline or after the load has been dumped, the springs 26 and 9 will act upon the tongue to cause it to again assume a horizontal position. During the raising or lowering of the tongue, the 60 rollers 22 of the clamping device will move rearwardly and forwardly to facilitate the maintenance of the spring 29 in its proper position and reduce the friction to a minimum. The angular positioning of the tongue 65 with respect to the vehicle can be varied to

suit the height of the draft animals by adjusting the straps 17 and 18 and nuts 16 and 19 on the screw threaded ends 14. These parts being adjusted upwardly to lower the tongue and downwardly to raise the tongue. 70

Although I have shown and described the preferred embodiment of my invention, I desire to be understood that I am not to be limited to the exact details shown, however, I desire that great stress be laid upon the 75 peculiar co-operation and arrangement of the resilient supporting means, the clamping means and the connecting means between the supporting and clamping means co-operating therewith for providing the efficient 80 spring tongue support.

From the above description taken in connection with the accompanying drawings, it can easily be seen that I have provided a device that is simple in construction, containing 85 but a few simple parts that can be cheaply manufactured and assembled and when assembled can be placed upon the market and sold at a minimum cost.

It will be understood that the above description and accompanying drawings comprehend only the preferred embodiment of my invention and that various minor changes in detail of construction, proportion and arrangement of the parts may be made within 90 the scope of the appended claims and without sacrificing any of the advantages of my invention.

I claim—

1. In a tongue support, the combination 100 with an axle and a tongue pivotally mounted with respect to the axle, of a pair of springs of different degrees of resiliency, said springs including coil and leaf springs, one of which is pivotally connected to the 105 tongue and slidably connected to the axle, while the other is connected to the tongue and to the first mentioned spring, and a support between the tongue and the leaf spring to provide a cantaliver suspension. 110

2. In a tongue support, the combination with an axle and a tongue pivotally mounted with respect thereto, of a leaf spring, one end of which is pivotally secured to the tongue, the other end of the spring being 115 slidably connected to the axle, a support secured to the tongue and connected to the leaf spring intermediate its ends, and a coil spring having a degree of resiliency different from that of the leaf spring, said coil 120 spring having one end secured to tongue and its other end connected with the leaf spring between the support and the slidable connection with the axle.

3. In a tongue support, the combination 125 with an axle and a tongue pivotally mounted with respect thereto, of a leaf spring having one of its ends pivotally secured to the tongue and its other end slidably connected to the axle, a coil spring connected 130

to the tongue and to the leaf spring adjacent its slidably connected end, and means to support the leaf spring intermediate the coil spring connection and the pivoted 5 curement, said means operating further to limit the leaf spring movement at which time the spring acts as a cantaliver.

In testimony whereof I affix my signature in presence of two witnesses.

JOHN M. PENN.
